UNITED STATES PATENT OFFICE

152,470

DESIGN FOR A COOKY JAR OR SIMILAR ARTICLE

Nettie E. Graven, Wooster, Ohio

Application November 12, 1947, Serial No. 142,469

Term of patent 14 years

(Cl. D58—25)

To all whom it may concern:

Be it known that I, Nettie E. Graven, a citizen of the United States, residing at Wooster, in the county of Wayne and State of Ohio, have invented a new, original, and ornamental Design for a Cooky Jar or Similar Article, of which the following is a specification, reference being had to the accompanying drawing, forming part thereof.

Fig. 2 is a side elevational view thereof; and

Fig. 3 is a top plan view thereof.

I claim:

The ornamental design for a cooky jar or similar article, substantially as shown.

NETTIE E. GRAVEN.
